ABSTRACT: A lamp comprises an envelope within which is disposed a source of electromagnetic radiation. A coating of a "high-temperature phosphor" and coating of a "low-temperature phosphor" are provided on discrete regions of the inner surface of the envelope of the lamp so as to operate at respectively a higher and lower temperature during normal working of the lamp.

LAMP HAVING TWO SEPARATE PHOSPHOR COATINGS

The present invention relates to lamps in which phosphors are irradiated by electromagnetic radiation so as to emit visible light.

During the operation of such a lamp, heat energy is transferred to the phosphor causing its temperature to rise. For a given phosphor, undergoing a particular excitation, there will be a relationship between the temperature of the phosphor and the amount of light emitted. In some cases the phosphor emits more light as the temperature is raised; in others the amount of light emitted falls with increasing temperature.

The total light output of such a lamp is made up by the light emitted by the phosphor plus the part of the irradiating radiation that is within the visible region of the spectrum.

The source of the irradiation in such a lamp may conveniently be a mercury arc-tube.

The color rendition properties of such a lamp suffer because of the lack of certain wavelengths in light emitted by the discharge tube, there being present only light of the bands of wavelengths characteristic of the discharge. In an attempt to improve the color rendition properties phosphors are included in the lamp, the light emitted from which is of such wavelengths as will complement the visible light output of the discharge tube by providing some of the missing wavelengths.

According to the present invention there is provided a lamp comprising a source of electromagnetic radiation mounted within an envelope of the lamp, a coating of a "high temperature phosphor" provided on a first region of the inner surface of the envelope provided on a second region of the inner surface of the envelope, the first region of the envelope having a higher working temperature during normal operation of the lamp than the second region.

In this specification the expressions "high temperature phosphor" and "low temperature phosphor" mean respectively a phosphor having a maximum output of light for the excitation occurring in normal working of the lamp at a higher temperature and a phosphor having a maximum output of light for the excitation occurring in normal working of the lamp at a lower temperature.

The lamp may include more than two phosphors, the, or each, further phosphor being so arranged as to operate at a predetermined temperature dependent on the relationship between its emission of light and operating temperature.

The invention will now be described by way of example with reference to the accompanying drawings, in which:

FIG. 1 shows a reflector type lamp operating in a vertical condition;

FIG. 2 shows an elliptical lamp operating in a horizontal condition;

FIG. 3 is a graph showing the variation in the temperature of the amount of light emitted by phosphor 'B';

FIG. 4 is a graph showing the variation with temperature of the amount of light emitted by phosphor 'A', and

FIG. 5 shows the total light energy output of the lamp shown in FIG. 1.

FIG. 1 shows diagrammatically a reflector bulb type lamp. This bulb is arranged to operate with its axis vertical and its capped end uppermost. The temperature distribution on the outer envelope of the bulb is indicated in FIG. 1. The envelope carries on its inner surface two discrete phosphor coatings. A coating of a first phosphor, phosphor A, is arranged on a portion of the envelope having a relatively high operating temperature and a coating of a second phosphor, phosphor B, is arranged on a portion of the envelope having a relatively low

operating temperature.

The variation of the amount of energy emitted by phosphor A at various temperatures is shown in FIG. 4 and that for phosphor B in FIG. 3. It is clear that for the lamp to operate at maximum light output efficiency, the operating temperature of phosphor A should be between 240° and 400° C. and that of phosphor B between 55° and 245° C. This is ensured by limiting the coating of phosphor 'A' to the region nearer the cap which, in normal operating conditions, will be at a higher temperature than the region further from the cap on which the coating of phosphor 'B' is provided.

The particular phosphors used in the lamp are chosen by reference to known light emission/temperature characteristics of phosphors. In the example described above phosphor A is yttrium-vanadate and phosphor B is magnesium fluorogerminate.

FIG. 5 shows the total output of the lamp in the visible region of the spectrum. The square peaks are the output of the mercury arc-tube in the visible region and the smoother peaks the contributions from phosphors A and B. It is seen that the light from the phosphors fills in bands of the spectrum in which the mercury arc-tube is deficient.

Although in the embodiment described above only two phosphors are shown, it is possible to use more than two phosphors. In a further embodiment, a coating of a third phosphor is provided at a position in which its operating temperature will be intermediate that of phosphor 'A' and phosphor 'B' such a phosphor could be europium activated strontium silicate coatings a more complete visible spectrum can be built up to provide an increase in total lumens and to improve the color rendition properties of the lamp.

In an alternative embodiment FIG. 2 is shown. This embodiment shows an elliptical lamp which is adapted for mounting in a fitting to operate in a horizontal condition. During such operation, there is a temperature differential between the top and the bottom of the lamp. Phosphor 'A' is coated on the upper part of the inner bulb surface and phosphor 'B' on the lower part. The approximate temperatures shown in FIG. 2 are for the lamp operating in free air. The temperature would be higher if the lamp were operated within a fitting in which case the fitting design will influence the final temperature differential.

The embodiments of the invention in which an exclusive property or privilege is claimed are defined as follows:

1. A lamp comprising:
an envelope,
a source of electromagnetic radiation within said envelope,
a first region on the inner surface of the envelope being
adapted to run at a relatively high temperature,
a second region on the inner surface of the envelope being
adapted to run at a relatively low temperature,
a coating of a "high temperature phosphor" disposed on
said first region,
a coating of a "low temperature phosphor" disposed on
said second region.

2. A lamp as claimed in claim 1, wherein one end of the envelope is closed by a cap and the lamp has a normal working position in which its axis is vertical and its capped end uppermost, said first region being nearer said capped end than said second region.

3. A lamp as claimed in claim 1 in which the "high temperature phosphor" is yttrium-vanadate.

4. A lamp as claimed in claim 1, wherein the "low temperature phosphor" is magnesium fluorogerminate.
